GARMENT BAG

William M. Moore, Maywood, Ill.

Application May 24, 1933, Serial No. 672,661

2 Claims. (Cl. 206—7)

This invention relates to certain novel improvements in garment bags.

An object of this invention is to provide a new and improved garment bag.

5 Other objects of the invention are: to provide a new and improved transparent garment bag; an improved top reinforcement for the bag to prevent tearing of the same; and to provide a novel protector enveloping the garment hanger.

10 Other objects will appear hereinafter.

The invention consists in the novel combination and arrangement of parts to be hereinafter described and claimed.

15 The invention will be best understood by reference to the accompanying drawing, showing the preferred form of construction, and in which:

Fig. 1 is a perspective front view of a preferred form of the new bag;

Fig. 2 is a longitudinal sectional view on line 2—2 in Fig. 1;

Fig. 3 is a fragmentary perspective rear view of the new bag;

Fig. 4 is a perspective view of the bag top insert and reinforcing member; and

25 Fig. 5 is a perspective view of a preferred form of garment hanger protector embodied in the invention.

The new garment bag is generally indicated at 10 and is preferably made of suitable transparent material such as, for example, "Cellophane."

The bag 10 includes a body 22 having seams 11 suitably joined together at the rear of the bag, as by means of adhesive or otherwise. The bag 10 may be made in any desired or standard com-

35 mercial lengths suitable for suits, dresses, waists, shirts, coats, and other garments, and because of its transparency it affords opportunity for display of the garment therein and for inspection in the cleaner's or tailor's shop before delivery;

40 and likewise affords an opportunity to the driver and customer to inspect the garment therein before or at the time of delivery.

Secured to the bottom of the bag body 22 in any suitable manner, as by an adhesive, and ex-

45 tending transversely thereof, is a strip 11 which seals the bottom of the bag and renders that end of the same mothproof. This strip is preferably made of the same transparent material as that of which the binding of the bag is made.

50 Indicated at 12 is a strip or member which is inserted into and fastened inside the neck of the bag in any suitable manner as by means of an adhesive, so as to reenforce the neck of the bag and to prevent tearing or ripping the same in han-

55 dling or in inserting a garment into or removing

the same from the bag. The reinforcing strip 12 may be made of any suitable material but is preferably made of suitable transparent material, such as "Cellophane", to match the body of the bag and has formed therein a slot 13 for the passage of the garment hanger hook 14.

5 Indicated at 15 is a small strip which is adhesively secured to the rear of the bag at the top thereof and then folded down over, and pasted to, the front side of the bag to reenforce and mothproof the opening 13 at the top of the bag. This strip 15 is also preferably made of transparent material and has a slot 16 formed therein to accommodate the shank of the hanger hook 14.

10 Indicated at 17 is a form of protector for the garment hanger; this form of protector also preferably being made of suitable transparent material such as "Cellophane."

15 The bag 10 is formed with an opening 18 in its neck which is later closed by the insert 12, except for the opening 13 which allows for passage of the shank of the hanger hook therethrough. The top of the bag may be closed in any suitable manner, as by folding the top edge 19 of the front side over upon the rear side and adhesively securing the same thereto.

20 The bag 10 is made with the bottom 20 thereof open and the garment is introduced into the bag through the open bottom 20 which is then closed and mothproofed by the strip 11 after the insertion of the garment 21.

25 While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

30 Having thus described my invention what I claim as new and desire to protect by Letters Patent is:

35 1. In a "Cellophane" garment bag comprising a tubular body having a closed end provided with an open neck, a "Cellophane" reinforcing member fastened to the inside walls defining the neck and having an opening aligned with the opening in the neck, a garment hanger comprising in part a hook member and two angularly arranged reaches, a "Cellophane" covering for the load bearing parts of the garment hanger and shaped to conform to the angular reaches and having an opening receiving the hook member, the neck 40

- of said garment bag being shaped to conform to the inclined reaches of said garment hanger, the said covering fitting snugly within the neck with the covering bearing against the inclined portions substantially throughout their entire length, and a "Cellophane" reenforcing strip slit to receive the hook portion and cemented to the outer surfaces of the neck, to reinforce the area surrounding the opening therein.
2. In a "Cellophane" garment bag comprising a tubular body having a closed end provided with an open neck, a "Cellophane" reenforcing member fastened to the inside walls defining the neck

and having an opening aligned with the opening in the neck, a garment hanger comprising in part a hook member and two angularly arranged reaches, and a "Cellophane" covering for the load bearing parts of the garment hanger and shaped to conform to the angular reaches and having an opening receiving the hook member, the neck of said garment bag being shaped to conform to the inclined reaches of said garment hanger, the said covering fitting snugly within the neck with the covering bearing against the inclined portions substantially throughout their entire length.

WILLIAM M. MOORE.
